MICHIGAN.

BUTTER-DISH.

1,027,719.

Specification of Letters Patent.

Patented May 28, 1912.

Application filed December 23, 1911. Serial No. 667,494.

To all whom it may concern:

Be it known that we, ALEXANDER A. FORDON and GEORGE L. MORRISON, citizens of the United States, residing, respectively, at Detroit and Hudson, counties of Wayne and Lenawee, State of Michigan, have invented a certain new and useful Improvement in Butter-Dishes, and declare the following to be a full, clear, and exact description of the same, such as will enable others skilled in the art to which it pertains to make and use the same, reference being had to the accompanying drawings, which form a part of this specification.

15 Our invention relates to new and useful improvements in butter plates of which the following is the specification, its object is to produce a simple, cheap dish for that purpose and which more especially can be nested in transportation.

In the drawings:—Figure 1, is a plan view of a dish, one end being formed or shaped and the other end in the process of formation. Fig. 2, is the right end view of Fig. 1. Fig. 3, is a side view of one end. Fig. 4, is a view of the blank of which the dishes are formed in reduced scale. Fig. 5, is a similar view, particularly on the line $\alpha-\alpha$ of Fig. 1 but showing how two dishes are nested, both of which are sectioned.

30 In the drawings, similar letters refer to similar parts.

In the drawings, A represents a blank formed from tough cardboard or paper of the outline shown in said figure. Considering the view to be the inside and bottom of the dish when formed, the lines $\alpha-\alpha$ are the first lines of folds with an interior angle, the ends B, B, being raised by such folding 40 and then forming a second fold, on the dotted lines $b-b$, with an external angle toward the observer, as shown in Fig. 1. In scoring $b-b$, and $a-a$, inclose a triangular or gusset portion. As these folds are carried to 45 the point of bringing the surfaces all in contact, as shown at the right hand side of

Fig. 1, and the end view of Fig. 2; the sides C, C, are brought into a lateral position by folding to an obtuse angle along the lines $c-c$ and with a corresponding angle to the end piece A' formed along the angle c' . When these are closed as at the right hand of Fig. 1, one staple D is fastened through all of the thicknesses holding them all in position and when both ends are thus fastened, the dish is completed having an external form as shown in the end view of Fig. 2. In this manner, but one staple is used for each end and the blank contains no indentations or other cutting than merely 50 shaping in the form in Fig. 4 and both ends can be folded and fastened in one operation. When so folded, and fastened, they nest as shown in Fig. 5 in which the exterior of the dish is shown as E and the interior dish is 55 shown as F, it being obvious that any number of dishes can be nested, a sectional view of two only is shown. It will be noted that when so formed, the angles G H overlap, are fastened together and reinforced by the 60 remaining folds and end part J. This makes a very strong and stiff construction and if the material be waterproof, the dish is 65 watertight.

We are aware that dishes have been made 70 in which the corners have been folded and the end sections brought up on the inside of the dish, but with no overlapping of the extreme angles as we have shown. We have found in experience that such dishes will 75 not nest and therefore we have attained a result not before known by the improvement which we have hereinbefore described.

Having thus described our invention, what we desire to claim is:—

85 A butter dish, comprising a blank having a central rectangular scoring and a pair of divergent scorings extending from each corner of the rectangular scoring to the edge of the blank, forming the sides and end pieces 90 of the shape of a truncated triangle and separated from the sides by gussets of the

shape of inverted triangles, the gussets being folded on the inside of the end pieces and the end portions of the sides being brought together over the gussets and on 5 the inside of the end pieces, and means for fastening the end portions of the sides and the gussets to the end pieces, whereby in nesting the end pieces slide over the ledges formed by the folds of the end portions of 10 the sides and the gussets and nesting is readily accomplished, substantially as described.

In testimony whereof, we sign this specification in the presence of witnesses.

ALEXANDER A. FORDON.
GEORGE L. MORRISON.
